UNITED STATES PATENT OFFICE.

MORRIS LIPSIUS, OF BROOKLYN, NEW YORK, ASSIGNOR TO ATLAS & BLUHM, INC., OF NEW YORK, N. Y., A CORPORATION OF NEW YORK.

DESIGN FOR A PRINTED FABRIC.

Application filed September 23, 1926. Serial No. 19,151. Term of patent 3½ years.

To all whom it may concern:

Be it known that I, MORRIS LIPSIUS, a citizen of the United States of America, and a resident of the city of New York, borough of Brooklyn, county of Kings, and State of New York, have invented a new, original, and ornamental Design for Printed Fabric, of which the following is a specification.

Reference is to be had to the accompanying drawing, in which the figure is a view of a swatch of fabric showing my new design.

I claim—

The ornamental design for a printed fabric as shown.

MORRIS LIPSIUS.
